UNITED STATES PATENT OFFICE.

ROBERT P. BROWN, OF PHILADELPHIA, PENNSYLVANIA, ASSIGNOR TO BROWN & BAILEY COMPANY, OF PHILADELPHIA, PENNSYLVANIA, A CORPORATION OF PENNSYLVANIA.

GOODS-FOLDER.

1,121,609.

Specification of Letters Patent. Patented Dec. 22, 1914.

Application filed December 5, 1912. Serial No. 735,052.

To all whom it may concern:

Be it known that I, ROBERT P. BROWN, a citizen of the United States, residing in the city of Philadelphia, county of Philadelphia, and State of Pennsylvania, have invented certain Improvements in Goods-Folders, of which the following is a specification.

My invention is designed primarily to provide simple, inexpensive, efficient and readily manipulated means of protecting goods of soft and frail character, liable to be crushed and crumpled in handling, such as silks, other light weight fabrics and garments made thereof.

Heretofore, in wrapping or boxing and delivering soft silks, other frail fabrics and articles made therefrom, they have been insufficiently protected by the usual wrapper, which offers no substantial resistance to the external pressure, and by the usual cardboard box, in which goods move about in handling, with the result that the materials or articles are liable to be delivered in crushed, crumpled and unsatisfactory condition.

I attain the objects of my invention, avoiding the foregoing defects of the prior art, by the use of a combined wrapper and collapsible box whereby the goods are infolded by the closely conforming flexible wrapper and held thereby from movement within the box which is erected to inclose the goods thus protected by the wrapper.

In the accompanying drawings, Figure 1 is a perspective view of a blank or expanded folder comprised in my invention, Fig. 2 is a perspective partly sectional view of the erected folder, Fig. 3 is a vertical section taken transversely through the erected folder shown in Fig. 2, Fig. 4 is a plan view of a modified form of blank or expanded folder comprised in my invention, and Fig. 5 is a perspective partly sectional view of the folder erected from the blank shown in Fig. 4.

As illustrated in Fig. 1, the blank comprises the bottom section 1, the side sections 2 and 2' hinged to the bottom section on the scored lines 3 and 3', the top section 4 hinged to the section 2 on the scored line 5, the side section 6 hinged to the top section on the scored line 7, the end flaps 8 hinged to the ends of the bottom section on

the scored lines 9, the end flaps 10 hinged to the ends of the side 2' on the scored lines 11, the end flaps 12 hinged to the ends of the side 2 on the scored lines 13, the end flaps 14 hinged to the ends of the top section 4 on the scored lines 15, and the end flaps 16 hinged to the ends of the side section 6 on the scored lines 17, the blank comprising these parts being paper or cardboard of reasonably rigid and strong material adapted for providing a comparatively stiff box when erected.

The wrapper 18 is a flexible sheet (preferably of comparatively light paper having a comparatively rough surface offering frictional resistance to the movement of a fabric therein), which is secured along its edge 18' to the box section 2', the wrapper being of such character that a frail fabric or garment can be rolled within it or infolded by it upon the bottom section 1 of the box blank and such blank erected about the folded package.

As shown in Figs. 2 and 3, the rolled or loosely folded wrapper 18, when brought to position on the bottom section 1, brings the side section 2' (to which it is fixed and by which it is therefore held) to the erected position. Then the side section 2' is brought to the erected position, the top section 4 is folded down parallel to the bottom section, the side section 6 is folded down against the side section 2', the end flaps 10, 12 and 16 are folded in and the end flaps 8 and 14 are folded over them.

As shown in Fig. 4, the blank is composed of the bottom section 20 having the end sections or flaps 21 hinged thereto on the scored lines 22 and comprising the lugs 21' hinged on the scored lines 22', the side section 23 hinged to the bottom section 20 on the scored lines 24 and having the end sections or flaps 25 hinged thereto on the scored lines 26, the top section 27 hinged to the side section 23 on the scored line 28, the side section 29 hinged to the top section 27 on the scored line 30 and having the end sections or flaps 31 hinged on the scored lines 32, and the bottom section 33 hinged to the side section 29 on the scored line 34 and having the end sections or flaps 35 hinged thereto on the scored lines 36 and comprising the lugs 35' hinged on the scored lines 36', the several parts of this blank being preferably

made of card or paper board having sufficient weight and stiffness to provide a comparatively rigid box.

A flexible wrapper 37, preferably of light paper having a comparatively rough surface, has its edge 37' secured, as by glue, to the bottom section 20, such wrapper being adapted for infolding a garment or fabric brought thereby upon the section 20. The wrapped goods being upon the bottom 20 of the box blank, the flaps 21 and the lugs 21' are turned in over the ends of the goods which are rolled within the parts 23, 27, 29 and 33, when the ends of the part 27 engage the lugs 21'. The parts 25 and 31 are then turned in against the parts 21, the parts 35 are folded over the parts 25 and 31, and the lugs 35' are tucked under the ends of the part 27, forming the erected construction with parts interlocked to maintain the box in the erected position as illustrated in Fig. 5. The peculiar double tuck used at the ends of the erected box has the combined advantages of affording a desired protection for the ends of the goods and a desired lock for maintaining the parts in the desired erected relation.

As the inner flap with the lug thereon is folded over the goods before the blank is transposed into box form, the goods are not only protected in the further operation of folding the parts of the blank in erecting the box but particularly in tucking in the ends. It will be understood that the flexible sheet may be omitted from the form of the construction shown in Figs. 4 and 5 and

a highly desirable construction, within my invention, will remain.

Having described my invention, I claim:

1. A primarily flat relatively stiff blank, 40 having longitudinal and transverse scores providing side, bottom and top sections, together with end tucks, adapted to be erected and interlocked to form a rigid box; in combination with a primarily flat relatively flexible 45 wrapping sheet permanently secured to one of said sections, approximately coextensive in length therewith and adapted to be folded about goods so as to prevent them from moving in the erected box in which 50 they are inclosed.

2. A primarily flat relatively stiff blank, 55 having longitudinal and transverse scores providing side, bottom and top sections, together with end flaps, adapted to be erected 60 and held in interlocking relation to form a rigid box; in combination with a primarily flat relatively flexible wrapping sheet permanently secured to one of said sections and extending away from the blank and substantially coextensive in length therewith and having a comparatively rough surface, whereby goods may be wrapped and held so as to prevent them from moving in the erected box. 65

In testimony whereof I have hereunto set my hand this 29th day of November, 1912, in the presence of the subscribing witnesses.

ROBERT P. BROWN.
